SHOE SEWING MACHINE

Arthur Bates, Leicester, England, assignor to
United Shoe Machinery Corporation, Paterson,
N. J., a corporation of New Jersey

Application September 11, 1928, Serial No.
305,200, and in Great Britain September 14,
1927

3 Claims. (Cl. 112—35)

The present invention relates to shoe sewing machines.

In the manufacture of some types of shoes it is necessary to employ sole materials such as thin leather, crepe rubber, or combinations of felt and leather, which from the standpoint of thread holding characteristics are inherently weak. This is particularly true of turn shoes in which the inseam does not penetrate from face to face of the sole. In the case of shoes or slippers made with leather soles, the proper between substance to hold the stitching places limits upon the thinness and texture of the leather and in case of crepe work, it is very difficult to sew with the desired amount of tension since the row of thread lengths which lies on the sole itself is liable to cut into the material of the sole.

The principal object of the present invention is to provide a machine particularly adapted to manufacture a turn shoe or slipper which may be made with a sole of very thin leather, crepe, felt, or material which from the point of view of its stitch holding character is of inferior grade.

With this object in view, one feature of the invention contemplates the provision in a sewing machine of devices for producing a shoe in which the holding of the individual stitches is assured by a strip or cord of material interposed between the individual thread lengths and the surface of the sole and which passes alternately on opposite sides of the stitch holes. The strip or cord is preferably of thicker material than the seam thread, in order to afford considerable supporting surface for the thread against any possibility of pulling or cutting into the material of the sole.

Further features of the invention consist in novel features of sewing machine construction and combinations and arrangements of parts hereinafter described and particularly defined in the claims.

In the accompanying drawing, Fig. 1 is a side elevation of so much of the parts of a sewing machine of the type referred to as is necessary for an understanding of the present invention; Fig. 2 is a view similar to Fig. 1 showing a machine for operating on an unchanneled shoe; Fig. 3 is a front elevation of the lower end of the thread laying mechanism showing its relationship to the needle; Fig. 4 is a view similar to Fig. 3 showing a modified form of the invention; Fig. 5 is a perspective view showing the thread layer and its operating mechanism; Fig.

6 is a view showing a seam sewn on the machine of the present invention; and Fig. 7 is a fragmentary view of a turn shoe according to the present invention.

The illustrated machine comprises a curved hooked needle turn shoe sewing machine which has the general organization of the machine described in the patent to Bates No. 1,188,388 and Bates and Richards No. 1,188,389. The machine has the usual stitch forming devices preferably of the general form disclosed in the prior patents above referred to.

Referring to the drawing, the machine has a curved hooked needle 1 oscillating in a fixed plane, the usual looper 2 and thread finger 3. A feed member illustrated generally at 4 in Fig. 1 is employed to feed the work. As shown in Fig. 1, the machine is adapted for sewing an upper 5 to a channeled sole 6 and the feed member comprises a four-motion channel guide of the usual form. In the manufacture of a shoe with an unchanneled sole as shown in Fig. 2, the feed member may comprise any usual or preferred feeding device, such as a four-motion pricker.

In either form of the machine, whether for sewing an unchanneled or a channeled sole, the shoe without being lasted is supported on the rotary horn 7, the upper 5 being turned over the edge of the sole 6.

In order to provide for laying the reinforcing strip or cord, a thread layer 8 is provided which is adapted to swing in a vertical plane in proximity to the needle. The arm 8 is fixed in one arm of a bell crank lever 9 pivoted on a shaft 10, which is fixed in the frame of the machine and which is parallel to the cam shaft 11 and about four inches practically directly above the sewing point. The thread laying arm is actuated by a link 12 which is pivotally connected to the bell crank lever 9 and at an intermediate point to an arm 13 pivoted on the frame of the machine. The link carries at one end a cam roll 14 which enters a cam groove in a gear 15 mounted on a stud 16, which stud is journalled in the machine frame with its axis parallel to that of the cam shaft. The gear 15 meshes with a pinion 17 on the cam shaft, the gear ratio being such that the gear 15 makes a complete revolution for every two revolutions of the cam shaft.

As shown in Fig. 3, the thread laying arm 8 as viewed from the front of the machine, oscillates in a plane slightly to the left of the plane of the needle. The motion of the arm as imparted by the link 12 is between the positions

shown in full lines and in dot and dash lines in Fig. 2. At the lower end, the thread laying arm delivers a reinforcing cord 20 through a suitable eye 30, the thread being supplied from 5 a cap over a suitable tension device 21, a spring pressed take-up arm 22, and a guide pulley 23 on the end of the link 12. The cord may pass directly from the pulley 23 to the eye 30, but preferably as shown in Fig. 3, it passes through 10 two eyes 31 and 32 in the arm above the eye 30, from one side to the other and back, in order to control its passage near the lower end of the arm and to prevent its catching when moving near the needle.

15 As shown in Fig. 3, wherein the plane of oscillation of the thread laying arm is slightly to the left of the plane of oscillation of the needle, that is, between the plane of the needle and the thread finger 3, the arm 8 is provided with a 20 gradual taper 26 to form a blade-like end, enabling it to pass to and fro freely with its cord in its eye in the narrow passage afforded between the needle on the one side and the thread finger and looper on the other. When the 25 thread laying arm is in the position indicated in full lines in Fig. 2, that is, in its foremost position as viewed from the front of the machine, its lower end is about one and three-quarters inches horizontally in front of and about 30 three-quarters of an inch higher than the lowest point in the needle path. At the rearmost position of the thread laying arm, as indicated in dot and dash lines, the lower end of the arm is practically one-quarter of an inch directly 35 above the lowest point of the needle path. The cam which oscillates the thread laying arm is so designed as to cause the arm to dwell successively in its extreme positions.

With its lower end in its forward position 40 as shown in full lines in Fig. 2, the arm 8 dwells during the time that the needle 1 is looped and then fully retracted. When the needle starts to advance on the following stitch, the arm 8 starts to move back, the arm and the needle passing 45 each other just after the needle reaches fully advanced position. The lower end of the arm reaches its fully retracted position, that is, as shown in dot and dash lines, just after the thread finger 3 commences to move back in the usual cycle of its movements. The thread laying arm dwells in the retracted position during 50 the time that the needle is again looped and retracted. During the next advancement of the needle, the arm 8 starts its forward motion approximately as the needle point is passing by the 55 side of the thread finger 3. Shortly after the needle reaches fully advanced position, the lower end of the arm 8 passes forwardly between the needle 1 on the one side and the looper 2 and thread finger 3 on the other side, and reaches 60 its fully advanced position approximately at the same time that the thread finger 3 reaches its retracted position and the looper 2 starts its looping movement by a movement to the right 65 behind the needle point. In this manner it will be seen that the thread laying arm is alternately in front and in the rear of the needle and looper for successive looping operations.

In the modified arrangement shown in Fig. 4, 70 the thread laying arm 8 oscillates in the same vertical plane as the needle. In this case the thread laying arm may be formed with a broader point, the tapered formation shown in Fig. 3 being unnecessary because of the greater 75 clearance between the arm 8 and the thread

finger and looper. In this modification, the arm operates in substantially the same cycle of movements as the arm in the construction shown in Fig. 3. In the forward position of the arm, it is permitted to dwell while the needle 80 is looped and retracted. As the needle starts to advance, the lower end of the arm 8 starts to retract from its forward position, the needle and the arm passing about one-eighth of an inch from each other, the arm reaching retracted position just after the needle has reached fully advanced position, and immediately before the thread finger 3 commences to move back. The arm 8 dwells in its retracted position during the time that the needle is again looped, retracted, and started on its advancing movement, the arm 8 commencing its forward movement just as the needle commences its forward movement and reaching its fully forward position just after the needle has reached its forward position. 90

95 A fragmentary view of a turn shoe or slipper made according to the present invention is shown in Fig. 7, illustrating the upper 5 attached to the sole 6 before the shoe is turned 100 right side out.

When the needle is looped with the lower end of the arm 8 in its retracted position, the cord extending to the eye of the arm 8 from its last anchorage to the work passes through the closed area bounded by the needle thread extending from the last stitch hole to the needle, by the needle projected from the sole and the sole itself, while on the other hand, when the needle is looped with the lower end of the thread laying arm in forward position, the cord does not pass into that area. 105

110 It will be seen that the cord lies under each thread length 24 extending between consecutive stitch holes, that is, it lies between the thread length and the sole. The cord is preferably of heavier and thicker material than the thread, so that as viewed from above the sole, the cord appears only slightly undulated and the thread 115 appears to zigzag above it from one stitch hole to the next. The relatively heavier cord not only affords a sufficient surface of engagement with the sole to prevent its cutting therethrough, but also makes a support for a considerable portion of each thread length between stitch holes 120 to prevent them from cutting into the sole either at the stitch holes or at any position between them. The difficulties ordinarily encountered in applying the proper tension to the 125 thread in soles of crepe rubber, felt, thin leather, or other material of inherently weak thread holding characteristics are therefore avoided. 130

The invention is equally applicable to the manufacture of shoes with channeled and unchanneled soles. The former will be best adapted for leather soles, and the latter for crepe or so-called combination soles. In the unchanneled sole, a groove of small dimensions may be provided, if desired, to form a bed to accommodate the thread and the cord. 140

145 It will be understood that although the thread supporting medium 20 has been described as a cord, the invention is not to be considered limited to a cord but may include any flexible strip which is laid on opposite sides of the stitch holes and under the individual thread lengths. Moreover, the term "sole" as used herein may include either a sole having an actual tread surface or an insole. 150

Having thus described the invention, what is claimed is:

1. A turn shoe sewing machine comprising a curved hooked needle, a looper, an oscillating thread laying arm movable in a plane between the plane of movement of the needle and the looper, means for moving the thread laying arm having provision for causing the arm to dwell alternately in front and in the rear of the needle point for successive stitches to lay a cord between the individual thread lengths and the sole.
2. A turn shoe sewing machine having, in combination, a curved hooked needle for sewing the upper to the sole of the shoe by stitches which do not penetrate from the foot face to the

tread face, a looper, and means for laying a cord alternately on opposite sides of the needle point for successive stitches whereby the cord passes under the individual thread lengths and on opposite sides of the stitch holes.

3. A turn shoe sewing machine comprising a curved hooked needle, a looper, an oscillating thread laying arm movable in the plane of movement of the needle, means for moving the thread laying arm having provision for causing the arm to dwell alternately in front and in the rear of the needle point for successive stitches to lay a cord between the individual thread lengths and the sole.
